UNITED STATES PATENT OFFICE.

TALBERT R. MICHEALS, OF MONONGAHELA CITY, PENNSYLVANIA.

GLASS-WORKING MACHINERY.

SPECIFICATION forming part of Letters Patent No. 616,245, dated December 20, 1898.

Application filed April 12, 1898. Serial No. 677,274. (No model.)

To all whom it may concern:

Be it known that I, TALBERT R. MICHEALS, a citizen of the United States of America, residing at Monongahela City, in the county of Washington and State of Pennsylvania, have invented certain new and useful Improvements in Glass-Working Machinery, of which the following is a specification, reference being had therein to the accompanying drawings.

This invention relates to certain new and useful improvements in glass-machines; and it has for its object to provide a machine for forming sheet or plate glass by pressing the same instead of performing the work in the manner which is now done.

The invention aims to provide such a machine in which the plate-glass when removed from the table is annealed in a special manner and the grinding which is usually done on glass of this character dispensed with.

To this end the invention consists, essentially, in a tension-table, above which is arranged the plunger which carries the molding-slab, and in the novel form of construction whereby this plunger is operated, together with the means for removing the glass plate from the table, where it may be engaged by the snaps by which the plate is handled while annealing.

In describing the invention in detail reference is had to the accompanying drawings, forming a part of this specification, and wherein like figures of reference indicate similar parts throughout the several views, in which—

Figure 1 is a perspective view of my improved glass-press, partially broken away. Fig. 2 is a longitudinal sectional view. Fig. 3 is a transverse vertical sectional view taken through the plunger and table. Fig. 4 is a like view taken through the table on a line in front of the plunger. Fig. 5 is a sectional view of the bracket through which the plunger-rod operates and showing a detail view of the cam-wheel for operating the plunger. Figs. 6, 7, and 8 are detail perspective views of the snap and stand employed for annealing the glass.

To put my invention into practice, I provide a suitable box or casing 1, upon which is supported and has secured thereto the frame 2. Arranged in the top of the casing 1, near its

forward end, is a depressible table 3, which is normally flush with the top of the said casing and is supported by vertical rods or standards 4, having coil-springs 5, arranged thereon within the casing, which serve to return the depressible table to its normal position after the weight of the plunger has been relieved from the same. Arranged centrally of the table 3 is the receiving-slab 6, which is composed of highly-polished stone, steel, or other suitable material. The molten glass from which the sheet or plate is to be formed is placed upon this slab 6 and is flattened into form by means of the forming-slab 7, which is arranged directly above the slab 6 and is secured to the plunger-rod 8, which is guided by a bracket 9, formed integral with the frame or secured thereto, as may be desired.

Arranged around the forming-slab 7 is a quadrangular frame 10, which projects below the said slab 7, so that it will engage around the edge of the receiving-slab 6 and prevent the glass being forced outward between the two edges of the slabs during the forming process. A vertical movement is imparted to this quadrangular frame, so that no impediment will be offered to the close engagement of the two slabs, and this may be accomplished by forming the two lugs 11 on the slab 7 and forming the quadrangular frame 10 with lugs 12, having bolts 14 rigidly secured therein and operating in the lugs 11. In order to guide the forming-slab 7, I also provide the same with lugs 15, which engage in the grooved standards 16, supported by the table 3 and acting as guides for the said forming-slab. The forming-slab and plunger are operated by means of the longitudinally-extending shaft 17, journaled in the framework and having a four-armed wheel 18 mounted upon its forward end. To one of these arms is pivotally connected the one end of the lever 19, the other end of which is pivotally connected to the inner face of the plunger-rod 8. This shaft may be provided on its rear end with a counterbalance-wheel 20. This shaft 17 has rigidly mounted thereon a sprocket-wheel 21 to receive the sprocket-chain 22, engaging the same and engaging the sprocket-wheel 23, which is rigidly mounted upon a longitudinally-extending shaft 24, also mounted in the frame 2 and directly un-

derneath the shaft 17. The sprocket-wheel 21 and the sprocket-wheel 23 may be substituted by pulleys to receive a belt in lieu of the chain 22. The sprocket 23 carries a radial flange 24, provided with notches 25, which are adapted to receive the clutch-pins of the clutch 26, the latter being formed with a pulley to receive the drive-belt.

Loosely mounted upon the pulley 27, near its forward end, and which may be retained in its position by a rigid collar 28 is a cross-head 29, carrying rods 30, which connect with the cross-head 31 after passing through the cross-piece 32 of the frame. To this cross-head 31 is connected the one end of the cord or chain 33, the other end of which is attached to a spool 34, rigidly mounted upon a transversely-extending shaft 35, which is journaled in the framework and is provided on its one end with an operating-wheel 36, having a locking-lever 37, which engages against the stop or lug 38, provided therefor on the side of the frame 2. The clutch is held normally in engagement by means of coil-springs 39, arranged upon the rods 30 between the cross-piece 32 and the cross-head 29. Arranged upon the top of the box or casing 1, directly in line with the slab 6 and at the rear thereof, is a carrier and deliverer 40, provided with a forked or bifurcated forward end 41, forming the springs which are adapted to engage underneath the sheet or plate of glass and upon which the same rests while it is being carried forward to the snap. This carrier and deliverer is provided on its upper face with ribs 42, which serve the same purpose as cogs and are adapted to be engaged by the ribbed or cogged wheel 43, mounted upon a transversely-extending shaft 44, journaled in suitable bearings 45, provided therefor on the frame 42, and which is provided on its one end with an operating-handle 46. Thus the carrier and deliverer is moved forward or backward, according to the direction in which the shaft 44 is rotated. For the purpose of elevating the sheet or plate of glass after the same has been formed upon the slab 6 I provide this slab at each of its corners with cut-away portions, in which are located the vertically-moving elevating-pins 47, which conform to the shape of the cut-away portions and complete a perfect square or other shape of slab which may be used. These elevating-pins 47 are connected to a plate 48, arranged underneath the depressible table 3, and carries a bearing 49, in which is journaled a cog or spur gear 50, adapted to be engaged by the spur-gear 51, which is eccentrically mounted upon the transversely-extending shaft 52, the latter being journaled in the box or casing 1 and provided on its one end with the operating-wheel 53 and with the locking-lever 54, which engages against the stop or lug 55, provided therefor on the side of the said box or casing.

After the plate or sheet of glass has been formed upon the slab 6 and the forming-slab

has been elevated, so that the shaft 52 may be operated to cause the elevating-pins 47 to elevate the sheet or plate of glass to the position shown in dotted lines in Fig. 4, the carrier and deliverer is operated so as to thrust the same forward under the plate or sheet of glass, upon which it is allowed to rest while being carried forward from its mold and table into position to be received by the snap, and with a machine as heretofore described I prefer to use the form of snap which is shown in Figs. 6, 7, and 8 of the drawings, comprising a suitable base 55, to which are secured the standards 56, in the upper end of which is journaled a shaft 57, carrying on its one end a harp or fork 58 and on its other end provided with an operating-crank 59. Swiveled near the opposite end of the base 55 is a standard 60, provided in its upper end with a groove to receive the shaft 61, which carries the snap 62. This snap 62 may be provided with one closed and one open face and is used to receive the plate or sheet of glass from the carrier and deliverer. After it has received the plate the shaft is turned so as to bring the snap in alinement with the harp 58 and permit the harp to enter the said snap. The two will then revolve in unison during the annealing of the glass, and when the annealing has been finished the snap will be turned so as to deposit the plate or sheet on the harp or fork 58, and the snap is then withdrawn, the said sheet or plate being removed from the harp or fork in any desired manner. By such a machine a perfect sheet or plate of glass may be formed at each stroke of the plunger-rod, which brings the forming-slab 7 into engagement with the molten glass previously placed upon the receiving-slab 6, and as the eccentric connection of the plunger-rod with the lever 19 and wheel 18 causes the forming-slab to be elevated the sheet or plate of glass just formed is elevated from the slab 6 in the manner heretofore described, the carrier and deliverer is run forward, so that the plate or sheet may be engaged by the snap, the carrier and deliverer returned to its former position, and a sufficient quantity of molten glass again placed upon the receiving-slab 6 to be in position for the forming-slab 7 upon its succeeding downward stroke. The complete revolution of the wheel 18 is permitted by reason of the table 3 being 110 deppressible, and when the center of the revolution has been passed the springs 5 will immediately return the table 3 to its normal position.

In case it is desired to suspend the movement of the forming-slab 7 the shaft 35 is rotated so as to wind the chain 33 upon its spool 34, and consequently causes the cross-head 29 to withdraw the clutch from its engagement, so that the pulley 25 will revolve freely upon the shaft without rotating the sprocket 24 therewith. The shaft is locked in its position by means of the lever 37, and when the latter is disengaged from its stop 38

the springs 39 will return the clutch into engagement and again start the operation of the forming-slab.

Having fully described my invention, what I claim as new, and desire to secure by Letters Patent, is—

1. In a glass-machine, the combination of a deppressible table, a receiving-slab mounted thereon, a forming-slab arranged upon said receiving-slab, a vertically-moving frame carried by said forming-slab, adapted to surround the receiving-slab when the two slabs are in engagement, and means for operating the frames and slab, substantially as herein shown and described. 15

2. A glass-machine comprising a receiving-slab mounted on a deppressible table, a movable forming-slab, means for imparting motion thereto, pins operating through the receiving-slab for elevating the sheet or plate of glass therefrom, and suitable delivery means for said sheet or plate of glass after the same has been elevated, substantially as shown and described. 20

3. A glass-machine comprising a deppressible table, a receiving-slab mounted thereon, a movable forming-slab, a quadrangular frame carried by the latter, means for communicating motion to the forming-slab, pins operating through the receiving-slab to elevate the sheet or plate of glass to allow its removal therefrom, substantially as shown and described. 25

4. In a glass-machine, a deppressible table, a receiving-slab mounted thereon, a forming-slab arranged above said receiving-slab and operating thereon, means for imparting motion thereto, and elevating-pins operating through said receiving-slab to elevate the sheet or plate of glass after the same has been formed, substantially as shown and described. 30

5. In combination with a frame, a deppressible table, a receiving-slab mounted thereon, a forming-slab, means for imparting motion thereto, and means arranged in the frame for suspending motion to the forming-slab, substantially as shown and described. 45

6. In a glass-machine, a deppressible table, a receiving-slab mounted thereon, a forming-slab arranged above said receiving-slab in vertical alinement, operating means for the forming-slab, and a carrier and deliverer adapted to receive the sheet or plate of glass from the receiving-slab, substantially as shown and described. 50

7. In a glass-machine, the combination of the box or casing, a deppressible table arranged therein, a receiving-slab mounted on said deppressible table, a forming-slab arranged above said receiving-slab, a quadrangular frame

surrounding the forming-slab and extending below the same, suitable guides for the forming-slab and means for imparting or suspending motion to the forming-slab, substantially as shown and described. 65

8. In combination, the receiving-slab, the elevating-pins operating therethrough, means for raising and lowering said pins, the carrier and deliverer, means for operating the same, and a snap to receive the sheet or plate of glass from the carrier or deliverer, substantially as shown and described. 70

9. In a glass-machine a deppressible table, a receiving-slab mounted thereon, elevating-pins operating therethrough and means where- 75 by said pins are operated, substantially as shown and described.

10. In a glass-machine, the combination of a deppressible table, a receiving-slab mounted thereon, a forming-slab in direct alinement above said receiving-slab, a frame carried by said forming-slab to prevent the glass from being forced outward during the forming process, elevating-pins operating through said receiving-slab to elevate the sheet or plate of glass after the same has been formed, operating means for said pins, and suitable means for removing the sheet or plate of glass after the same has been elevated, substantially as shown and described. 85

11. In combination, the box or casing, the deppressible table, the receiving-slab mounted thereon, elevating-pins operating therethrough to elevate the sheet or plate of glass after it has been formed, means for raising 95 and lowering said pins, the carrier and deliverer, operating means therefor, and a snap adapted to receive the plate or sheet of glass from the carrier or deliverer to anneal the same, substantially as shown and described. 90

12. In a glass-machine the combination of a deppressible table, a receiving-slab mounted thereon, a forming-slab arranged above said receiving-slab in vertical alinement, operating means for said forming-slab, pins operating through said receiving-slab to elevate the sheet or plate of glass after the same has been formed, operating means therefor, a carrier and deliverer adapted to receive said sheet or plate of glass, operating means therefor, 105 and a snap adapted to receive the sheet or plate of glass from the carrier or deliverer to anneal the same, substantially as shown and described. 110

In testimony whereof I affix my signature 115 in the presence of two witnesses.

TALBERT R. MICHEALS.
